CLAIM

The ornamental design for a balance bike as shown and described.

DESCRIPTION

FIG. 1 is a rear and top perspective view of a balance bike, showing my new design;

FIG. 2 is a front and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of an encircled area labeled "9" in FIG. 3.

The broken lines depict portions of the balance bike in which the design is embodied that form no part of the claimed design.

The dot-dash lines in FIGS. 3 and 9 are provided for annotative purposes to graphically indicate the areas of enlargement. The dot-dash lines do not represent actual structure and do not form part of the claimed design.
